UNITED STATES PATENT OFFICE.

JAMES L. JUDGE, OF MINNEAPOLIS, MINNESOTA.

GAME APPARATUS.

1,199,564.

Specification of Letters Patent. Patented Sept. 26, 1916.

Application filed June 10, 1916. Serial No. 102,861.

To all whom it may concern:

Be it known that I, JAMES L. JUDGE, citizen of the United States, residing in Minneapolis, county of Hennepin, State of Minnesota, have invented certain new and useful Improvements in Game Apparatus, of which the following is a specification.

The object of this invention is to provide a game adapted alike for young and old, and 10 requiring a considerable amount of skill.

A further object is to provide a game apparatus of simple, inexpensive construction and one that may be played both indoors and out of doors.

15 The invention consists generally in the various constructions and combinations as hereinafter described and particularly pointed out in the claim.

In the accompanying drawings forming 20 part of this specification, Figure 1 is a perspective view of a game apparatus embodying my invention, Fig. 2 is a vertical sectional view, Fig. 3 is a view of one of the darts used in the game.

25 In the drawing, 2 represents the box portion of the game apparatus which may be constructed of wood, metal, pulp, or other suitable material, and may be of any desired size or shape. The box portion 2 is provided 30 with a strap 3 having an eyelet 4 therein so that the box may be hung upon any suitable support. The box 2 has a number of cells or recesses 5 therein. In the drawing I have shown a box constructed with nine of 35 these cells, but this number may be more or less as desired. The cells 5 are cone-shaped tapering from the front to the back. I prefer to mark the cell nearest the center of the box "Game", and approximately half 40 of the remaining cells I prefer to mark "Red" and the remainder "Black", though the proportion and colors may be varied. The cells 5 are also numbered and in the drawing I have shown the red cells numbered 5, 6, 4, 45 and 3, while the black cells are similarly numbered 5, 6, 4 and 3, though it will be understood that these numbers may be varied. The center cell as shown in the drawing is marked "Game".

50 I provide darts 7 one of which is shown

in detail in Fig. 3. The dart 7 consists of a shaft 8 constructed of wood or other suitable material, one end being equipped with a tip 9 of rubber or other suitable material, which will cause the dart to readily stick in 55 a cell. The other end of said dart is equipped with wings 10 which may be fastened to the shaft 8 by any suitable means and may be constructed of heavy paper, cardboard or other suitable material. I prefer to color half of the darts red and half black to correspond to the colors of the cells 5, though as stated above these colors may be varied. Each dart bears a number as shown in Fig. 3 so that the darts of the 60 respective players may be identified, and I prefer to have the numbers on the darts correspond with the numbers of the cells.

The method of playing the game which I prefer to call "dartcelle" is as follows: The 70 box 2 is hung up on any suitable support. Two or more persons may play the game and each person is provided with one of the darts 7, part of the players having red darts and part black darts. The players stand at 75 a predetermined distance from the box 2 and the object of the game is to throw the darts to lodge them in the cells 5 having colors corresponding to the darts. Thus a player holding a red dart must lodge the 80 same in a red cell in order to have his score credited with the number of points equal to the number of the cell. If, however, the player holding a red dart should lodge same in a black cell a number of points equaling 85 the number of said cell will be deducted from his score and vice versa, the same rules applying to players holding black darts. The winner of the game is the person having the greatest number of points to his 90 credit at the finish or whose score first totals a predetermined amount, except, however, if a person lodges his dart in the cell marked "Game" thereupon he wins the game at once.

In various ways the details of construction may be modified and still be within the scope of my invention.

I claim as my invention:

A game apparatus comprising a frame, having an upright front plate, provided with 95 100

a series of cells or pockets therein suitably marked to represent certain values in the game, and a dart adapted to be thrown from a distance and having an end to enter a cell and lodge therein, the player being credited in the game with the value represented by such cell.

In witness whereof, I have hereunto set my hand this 5th day of June 1916.

JAMES L. X JUDGE.
^{his}
mark.
